(57) **CLAIM**

The ornamental design for an electroporation gasket, as shown and described.

DESCRIPTION

FIG. 1 is a front, top, left perspective view of an electroporation gasket, showing the new design;

FIG. 2 is a rear, bottom, right perspective thereof;

FIG. 3 is a front view thereof;

FIG. 4 is a left view thereof;

FIG. 5 is a top view thereof; and,

FIG. 6 is a bottom view thereof.

The broken lines of uneven length illustrate the boundary of the claimed design and form no part thereof. The broken lines of even length depict portions of the electroporation device that form no part of the claimed design.
